2,180,630

LOCKING DEVICE

Thomas A. Hearn, Ludlow, Ky., assignor to The
Globe-Wernicke Company, Norwood, Ohio, a
corporation of Ohio

Application December 19, 1938, Serial No. 246,610

2 Claims. (Cl. 45—94)

This invention relates to locking devices, and more particularly to locking devices for office furniture, such as desks, file drawer cases and the like, in which there is a main key actuated lock by means of which a plurality of drawers may be locked.

Generally, the objects of my invention include the provision of an effective locking arrangement of the class described which will have numerous advantages from the standpoint of simplicity and economy of manufacture.

These and other objects of my invention, which will be pointed out in more detail hereinafter, or which will become apparent to one skilled in the art as the description proceeds, I accomplish by that certain construction and arrangement of parts, of which I shall now describe two exemplary embodiments.

Reference is now made to the drawing, forming a part hereof, and in which:

Figure 1 is a front elevation of a desk to which my invention may be applied.

Fig. 2 is a fragmentary sectional view, in perspective, taken on the line 2—2 of Fig. 1; and Fig. 3 is a horizontal cross-sectional view through a conventional multiple drawer case having vertical and horizontal rows of drawers, showing the application thereto of my invention.

Briefly, in the practice of my invention, I provide one or more vertically disposed rods, and means for moving them arcuately about an axis parallel thereto, whereby they enter into notches in the drawer runners.

In Figure 1, I have shown a conventional pedestal type desk, having a central drawer 10, and a series of drawers 11 in the pedestal thereof. The central drawer 10 is provided with a lock 12, and provision is made that when the drawer 10 is locked, the drawers 11 will also be locked.

Referring now to Fig. 2, I provide a channel-shaped bearing bracket 13, mounted on the rear wall of the pedestal in any desired manner. A second bearing bracket 14 is preferably mounted on the bottom wall of the pedestal. The brackets 13 and 14 form bearings for the main locking rod 15 which is formed to have the radius arms 16, the pivot portions 17 and 17a, (which have their bearings, respectively, in the brackets 13 and 14), and a bell-crank portion 18 extending from the portion 17 at substantially right angles to the radius arms 16. The locking rod 15 is biased in a clockwise direction by means of a spring 19 engaging the bell-crank portion 18 and fastened at its other end to the bracket 13. It will be noted that the upper

limb of the bracket 13, indicated at 13a, is shorter than the bearing limb 13b, and forms a limit stop for the bell-crank portion 18.

A lever 20 is bent at right angles, as at 21, and is thus pivotally mounted in the bracket 13, the portion 21 having a bearing in both limbs thereof. The lever 20 passes behind the bell-crank portion 18, through a slot 22 in the pedestal side wall, and extends into the central drawer space as indicated at 23. The lever 20 is biased in a counter-clockwise direction by spring 24, the other end of which is fastened to the pedestal side wall.

The arrangement of the parts thus far described is such that when the drawer 10 is fully closed and locked, the rear end thereof abuts the portion 23 of the lever 20, and pushes it clockwise to a point where it is out of engagement with the bell-crank portion 18, whose further clockwise movement is prevented by its abutment against the limb 13a of the bracket 13. When the drawer 10 is unlocked, the spring 24, acting through the lever 20, causes the drawer to spring slightly outward, and the lever 20, by abutting against the bell-crank portion 18, produces a counter-clockwise movement thereof, and of the locking rod 15.

The individual drawers 11 are provided with conventional runners 25, but these runners are extended rearwardly as at 26, and are equipped with a cam surface 27 and a notch 28.

As will now be clear from a consideration of Fig. 2, in which the drawer 10 is shown in locked position, the locking bar 15 is at the limit of its clockwise movement, where it engages in the notches 28 of any drawer which is fully closed. Any drawer which is accidentally left open, may be locked by simply pushing it all the way in, whereupon the rod 15 will ride up on the cam surface 27 against the tension of the spring 19, and will ultimately enter the notch 28 when the drawer is fully closed.

In Fig. 3 I have shown an arrangement, substantially identical in principle, in which my invention is applied to a case having a plurality of vertical rows of drawers to be locked. In this embodiment, a series of locking rods 15a, corresponding to the rod 15, are pivoted by links 16a, corresponding to the radius arms 16, about the point 17b, corresponding to the pivot portions 17 and 17a. The various rods 15a are connected for simultaneous movement by a bar 29 which is urged toward the left to impart clockwise movement to the rods 15a by means of the spring 19a. In this embodiment I have shown a plunger 55

type lock 30, the plunger 30a of which is connected to one arm of the bell-crank 18a pivoted at 17c, the other arm of which is connected to the bar 29. It will be clear that when the lock 30 is unlocked, the plunger 30a will spring outward, imparting a clockwise rocking movement to the bell-crank 18a, whereby the bar 29 is moved to the left and the respective rods 15a are moved to unlocked position.

In this embodiment I make provision for the locking of drawers which have accidentally been left open, on the drawers themselves. Hook members 31 are pivoted at the rear ends of the respective drawers, and are urged in a counter-clockwise direction by the springs 32. Thus, if a drawer has been left open after the lock 30 has been locked, it need only be pushed in, whereupon the cam surface 27a, cooperating with the rod 15a, will cause the hook 31 to rock in a clockwise direction until the drawer is fully closed, whereupon the notch 28a will engage the rod 15a by a clockwise rocking of the hook 31.

It will be understood that numerous modifications of my invention may be made without departing from the spirit thereof, and I therefore do not intend to limit myself otherwise than as pointed out in the claims which follow.

Having now fully described my invention, what I claim as new, and desire to secure by Letters Patent, is:

1. In combination with an article of furniture having a plurality of vertical rows of drawers, said drawers being provided with resiliently rockable hook portions having a cam surface thereon,

a number of vertical locking rods equal in number to the number of vertical rows of drawers, said rods mounted for arcuate movement about axes parallel thereto and being connected together for simultaneous movement, means urging said rods to open position, a plunger type lock for said article of furniture, and a connection between the plunger of said lock and said rods whereby when said lock is locked, said rods are moved to locking position, the resilient mounting 10 of said hook portions and said cam surfaces permitting the locking of a drawer by pushing it in after said lock has been locked.

2. In combination with an article of furniture having a plurality of vertical rows of drawers, 15 said drawers being provided with resiliently rockable hook portions having a cam surface thereon, a number of vertical locking rods equal in number to the number of vertical rows of drawers, links pivotally connected to the respective rods 20 and to said article of furniture, and a bar pivotally connecting all of said rods, whereby said rods, as a gang, may have arcuate movement about axes parallel thereto, spring means urging said gang of rods to open position, a bell crank 25 on one of said links, a plunger type lock for said article of furniture, the plunger of said lock being connected to said bell crank whereby when said lock is locked, said rods are moved to locking position, the resilient mounting of said hook 30 portions and said cam surfaces permitting the locking of a drawer by pushing it in after said lock has been locked.

THOMAS A. HEARN.
